UNITED STATES PATENT OFFICE.

OSCAR FANBERG, OF HENSLEY, WEST VIRGINIA.

SCRAPER.

Application filed August 31, 1926. Serial No. 132,759.

This invention relates to scrapers and is designed more especially as an improvement upon the structure disclosed in Patent No. 1,559,946 issued to me on November 3rd, 1925.

5 It is an object of the invention to render the structure more substantial, more efficient in operation, and better adapted for quantity production.

With the foregoing and other objects in view which will appear as the description proceeds, the invention resides in the combination and arrangement of parts and in the details of construction hereinafter described and claimed, it being understood that changes 15 in the precise embodiment of the invention herein disclosed may be made within the scope of what is claimed, without departing from the spirit of the invention.

In the accompanying drawings the preferred form of the invention has been shown.

In said drawings,

Figure 1 is a plan view of the scraper.

Figure 2 is a longitudinal section.

Figure 3 is a section on line 3—3, Figure 2.

25 Referring to the figures by characters of reference 1 designates a handle of any desired length on one end of which is fitted a ferrule 2 having its free end portion flattened out and broadened to provide a head 3 having depending side ears 4. The blade of the scraper has been indicated at 5 and is formed of a sheet of suitable metal having its longitudinal edge portions bent to provide a scraping portion 6 and a reinforcing portion 7. Fastened on the 30 concave face of the scraper blade is a plate 8 held in position by rivets or the like and provided with ears 9 extending perpendicularly therefrom. These ears are spaced apart so that the ears 4 will fit between them as shown particularly in Figure 1. A connecting bolt 40 is extended transversely through the ears 4 and 9 and is held in place by a nut 11 or the like. Mounted on that portion of the bolt between the ears 4 is a coiled spring 12 one

end of which bears against the inner surface 45 of the ferrule as shown particularly at 13 while the other end bears against the blade 5 as shown at 14.

It will be apparent from the foregoing description that under normal conditions the 50 spring by exerting a constant pressure against the blade 5, causes the upper portion of the blade to thrust against the end of the head 3 so that the blade will thereby be held normally in the position shown in Figure 2. 55 Consequently when the scraper is drawn toward the operator there is no danger of the same collapsing. However when the strip is thrust away from the operator the blade will ride over the surface of the ground and 60 any material accumulated thereon and will be free to swing to the dotted position shown in Figure 2 against the action of the spring 12. As soon as the scraper is lifted out of contact with the ground, however, the spring will 65 return the blade to its normal positions.

What is claimed is:

A scraper including a handle engaging ferrule having a broad flat end portion, down-turned ears integral with the sides of said end portion, a sheet metal blade having both longitudinal edges curved to reinforce the blade longitudinally, a plate secured to and extending longitudinally of the blade having spaced ears struck therefrom for receiving between them the ears on the end portion of the ferrule, a pivot bolt extending through all of the ears, and a spring mounted on the bolt and housed between the ears, one end of the spring engaging the end portion of the ferrule and the other end engaging the plate, thereby to hold the blade normally pressed against the free end of the flat portion of the ferrule at a point between the curved portions of the blade. 70 75 80 85

In testimony that I claim the foregoing as my own, I have hereto affixed my signature.

OSCAR FANBERG.
